UNITED STATES PATENT OFFICE.

MARTIN B. MC LAUTHLIN, OF MALDEN, MASSACHUSETTS.

ELECTRIC HOIST.

SPECIFICATION forming part of Letters Patent No. 740,166, dated September 29, 1903.

Application filed March 29, 1902. Serial No. 100,639. (No model.)

To all whom it may concern:

Be it known that I, MARTIN B. MC LAUTHLIN, of Malden, in the county of Middlesex and State of Massachusetts, have invented certain new and useful Improvements in Electric Hoists, of which the following is a specification.

This invention relates to electric motors, and particularly such as are used for hoisting or elevator purposes.

The object of the invention is to secure greater compactness and protection for certain parts, and this end I secure by constructing the motor in the manner hereinafter described and claimed.

Of the accompanying drawings, Figure 1 represents a longitudinal sectional view of an electric hoist constructed in accordance with my invention. Fig. 2 represents a plan view, partly broken away and in section. Fig. 3 represents a section on the line 3 3 of Fig. 1. Fig. 4 represents a section on the line 4 4 of Fig. 1. Fig. 5 represents a section on the line 5 5 of Fig. 1. Fig. 6 represents a section on the line 6 6 of Fig. 1.

The same reference characters indicate the same parts in all the figures.

In the drawings, 10 represents a base having vertical bearing-standards 11 12 13, in which are journaled the rotating parts of the mechanism. The armature and field of the motor are both mounted to rotate, the armature within the field, and the winding-drum of the mechanism I merge or incorporate with a portion of the field.

14 represents the winding-drum, having an outer periphery grooved at 15 to receive the hoisting-cable 16 and having cast with it the cores of the field-magnets 17 17. A flange or disk 18 is secured by bolts 19 19 to lugs 20, located between the field-magnet coils, said disk having a journal 21 formed on it and mounted in a bearing 22 in the standard 12. In the opposite end of the drum is bolted a flange or disk 23, having a journal 24 mounted in a bearing 25 at the upper end of the standard 11.

26 represents the armature, having trunnions 270 271 journaled in the winding-drum journals 21 24, which are made hollow for that purpose and provided with suitable bearing sleeves or bushings.

27 represents the commutator of the arma-

ture 26, and 28 28 represent the brushes carried by the disk 23 and suitably insulated therefrom. Fixed to the journal 24 is a shaft 29, bearing a series of collector-rings 30 30, connected with the various leads or wires 31 31, leading from the brushes and field-magnet windings and extending through openings 32 32 in the journal 24. A series of brushes or collectors 33 33, stationarily mounted on a support 34, run in continuous contact with the rings 30 and are connected with suitable wires, whereby the field-magnet and armature-circuits may be connected with suitable external points.

An advantage obtained by this construction is that ample room is provided for the collectors and brushes, avoiding opportunity for short-circuits, which would occur if the collectors were crowded within a limited space. This arrangement also leaves the web of the drum 14 free and allows the bearing 25 to be brought as close as desired to the drum, being, in fact, partly within the limits of the drum in the construction which I have illustrated.

The armature-trunnion 271 is carried outwardly and journaled in a bearing on the standard 13, and on said trunnion is fixed a pinion 35, meshing with a gear 36, attached to a counter-shaft 37, mounted in bearings in standards 12 and 13. Fixed to said counter-shaft is a pinion 38, meshing with a gear 39, attached to a second counter-shaft 40, journaled in bearings in the standards 12 13. On the inner end of the counter-shaft 40 is fixed a pinion 41, meshing with an internal gear 42, formed on the disk 18. In this manner the armature is caused to rotate at a relatively high speed with respect to the winding-drum 14 owing to the reducing-gearing, and the two rotate in the same direction. Any other form or system of gearing than that shown could be employed—as, for instance, worm-gearing—which would prevent the rotation of the winding-drum from causing that of the armature when no current was on or the load overbalanced the power of the motor. The reducing-gearing is suitably proportioned, so as to give the desired relative speed to the armature and field, the speed of the field and of the winding-drum being much slower than that of the armature, as required for the winding-drum

of a hoisting apparatus. The armature evidently rotates faster when running in the same direction as the field than it would have to rotate if the field were rotated in the opposite direction from the armature or were stationary, other things being equal—that is to say, for a given differential or difference in rotative speed between armature and field the armature rotates fastest when running in the same direction as the field. The advantage of this in connection with an elevator-hoist is that the armature takes longer to attain its full speed at starting, and hence gives a gradual acceleration or easy start to the car or other device connected with the hoist.

It will be noted that I secure great compactness by merging the winding-drum with one of the rotating parts of the motor and afford protection to certain parts, such as the armature, commutator, brushes, and a part of the gearing illustrated in the drawings as inclosed within the winding-drum. Compactness and economy of material are further secured by making the winding-drum constitute a part of the magnetic circuit of the field-magnets.

Although I do not wholly restrict myself to an integral field-yoke and winding-drum, yet the described arrangement enables me to use this or equivalent means, whereby the amount

of iron in the field-yoke may be decreased or rather merged in the metal of the drum and additional compactness secured over former apparatus of this class.

I claim—

1. In an electric elevating or hoisting apparatus, a rotary hoisting-drum carrying a rotary motor-field, an armature mounted to rotate within said drum and field, a journal for the drum having one or more conductor-channels, conductors occupying said channels for carrying the current to and from the drum, collectors on said journal connected with said conductors, and a bearing for said journal interposed between said collectors and the drum.

2. In an electric elevating or hoisting apparatus, a rotary winding-drum, a rotary motor-field carried thereby, an armature mounted to rotate within said drum and field, and gearing connecting said drum and armature and causing said armature to rotate in the same direction as the drum and at a greater speed, for the purpose specified.

In testimony whereof I have affixed my signature in presence of two witnesses.

MARTIN B. McLAUTHLIN.
